[57] CLAIM

The ornamental design for a hauling attachment, as shown and described.

DESCRIPTION

FIG. 1 is a perspective view of a hauling attachment showing my new design, the broken lines are for illustrative purposes only and form no part of the claimed design;

FIG. 2 is a front elevational view;

FIG. 3 is a rear elevational view;

FIG. 4 is a right side elevational view, the left side elevational view being a mirror image of that shown;

FIG. 5 is a top plan view; and

FIG. 6 is a bottom plan view thereof.
